BURNER CONTROL MECHANISM

Siegfried G. Isserstedt, Toronto, Ontario, Canada,
assignor to Minneapolis-Honeywell Regulator
Company, Minneapolis, Minn., a corporation of
Delaware

Application March 26, 1943, Serial No. 486,673

9 Claims. (Cl. 158—28)

The present invention is concerned with burner control mechanism and more particularly with mechanism of the type designed to detect the proper operation of the burner ignition means before permitting operation of the burner.

The object of the present invention is to provide a control mechanism for a burner motor and ignition means employing a single temperature responsive element to detect both the proper operation of the ignition means and also the establishment of combustion.

A further object of the invention is to provide such a burner control mechanism in which a timer serves sequentially to perform various steps necessary to placing the burner in operation and in which a temperature responsive element is effective to stop operation of the timer first if ignition has not been successfully established and finally if combustion is not established.

A still further object of the invention is to provide a burner control mechanism of the type set forth in the previous object in which the temperature responsive element is a thermocouple having its hot junction subjected to the heat produced by the ignition means and also to that produced by the burner flame.

A still further object of the invention is to provide such a burner control mechanism in which the thermocouple controls the energization of one winding of a relay, this winding being capable of holding the relay in its energized position but incapable of moving it to its energized position.

A further object of the invention is to provide a burner control mechanism in which provision is made for determining whether ignition has been successfully established and in recycling if it has not, with means for rendering a safety controller effective to stop operation of the mechanism after a plurality of such unsuccessful attempts have been made.

Other objects of the invention will be apparent from a consideration of the appended specification, claims and drawing of which the single figure is a schematic illustration of my burner control mechanism embodied in a burner control system.

Referring specifically to the drawing, an oil burner is designated by the reference numeral 10. This oil burner is of a conventional design comprising an oil burner motor 11 having motor terminals 12 and 13. The motor 11 operates in the conventional manner to operate a blower to force an atomized mixture of fuel and air through a burner nozzle 14. Associated with the oil burner is an ignition transformer 16. The second-

ary winding of this ignition transformer is connected through conductors 17 and 18 to a pair of ignition electrodes 19 and 20. These ignition electrodes 19 and 20 are effective when the ignition transformer 16 is energized to ignite the atomized fuel mixture issuing from nozzle 14.

The operation of the burner is controlled by a main control switch which is illustratively shown in the form of a room thermostat 25. This thermostat comprises a bi-metallic element 26 to which is secured a pair of yieldable contact blades 27 and 28, adapted sequentially to engage a pair of fixed contacts 29 and 30, respectively. Contact blade 27 and contact 28 are less widely spaced from each other than are contact blade 29 and contact 30. Thus upon contact blades 27 and 28 being moved to the left as occurs upon a reduction in the temperature to which bi-metallic element 26 is exposed, contact blade 27 engages with contact 29 before contact blade 28 engages with contact 30.

Power for operation of the burner control mechanism is supplied by a step down transformer 32 comprising a line voltage primary winding 31 and a low voltage secondary winding 33. The line voltage primary winding 31 is connected by conductors 34 and 35 to line wires 36 and 37 leading to any suitable source of power (not shown).

The burner control mechanism includes two relays 40 and 41. The relay 40 comprises a relay winding 42 and switch blades 43, 44, and 45 actuated thereby. The switch blades 43, 44, and 45 are adapted to engage fixed contacts 46, 47, and 48. The switch blades 43 to 45 and the contacts 46 to 48 are biased apart by any suitable means (not shown). Upon energization of relay winding 42, the switch blades 43 to 45 are moved into engagement with contacts 46 to 48.

The relay 41 comprises two windings 50 and 51 and a pair of switch blades 52 and 53. The switch blades 52 and 53 are adapted to cooperate with fixed contacts 54 and 55. An armature 56 is associated with relay winding 50 and an armature 57 with relay winding 51. The two armatures 56 and 57 are independently connected to switch blades 52 and 53 so that either armature may move the switch blades 52 and 53 into engagement with contacts 54 and 55 independently of the other armature. The winding 51 is connected by conductors 58 and 59 to a thermocouple 61. Thermocouple 61 is located adjacent to the ignition electrodes 19 and 20 and also adjacent the burner nozzle 14 in such a position that the hot junction is affected by the heat of the burner

flame as well as by the heat of the spark existing between electrodes 18 and 20 when the ignition means is operating properly. The armature 57 is of a material having a high permeability and the winding 51 as well as the conductors 59 and 60 are of extremely low resistance so as to utilize as fully as possible the electromotive force generated by thermocouple 61. Because of this, the winding 51 and armature 57 are capable of holding switch blades 52 and 53 in engagement with contacts 54 and 55 after they have been moved into such engagement by the previous operation of coil 58 and armature 56. It is to be understood, however, that coil 51 and armature 57 are incapable of moving the switch blades 52 and 53 into engagement with contacts 54 and 55 but are merely capable of holding them in such engagement after they have been moved. While the winding 51 and the armature 57 have been shown as a solenoid winding and core in order to simplify the illustration, it is to be understood in an actual relay it would be more desirable to employ an electromagnet type of unit with a pivoted armature so that the small amount of power available would be more effectively utilized.

A time switch is generally designated by the reference numeral 63. This time switch comprises a plurality of switches which are sequentially actuated by a thermostatic element 64 upon the latter being heated. While the element 64 may take the form of any thermal sensitive member which moves upon the application of heat thereto, I have shown for purposes of illustration a double helix bi-metallic element of the type disclosed in Parsons Patent 2,121,259, dated June 21, 1938. Such an element consists of a bi-metallic element wound in a form of a helix about a helical axis. Such an element, because of the large amount of bi-metal and its particular disposition, operates when heated to move in a straight line and to exert a substantial force in so moving. Furthermore, because of the length of the element, its resistance is appreciable so that it is capable of being heated by the passage of current therethrough. As a result, no external heater is necessary. The element 64 is connected to a pair of switch blades 65 and 66 and a pair of switch actuating arms 69 and 70. The switch blades 65 and 66 cooperate with contacts 67 and 68, respectively. Switch blade 65 is biased into engagement with contact 67 while switch blade 66 is biased out of engagement with contact 68. Upon the element 64 being heated so that the right hand end thereof moves to the left, switch blade 65 is moved out of engagement with contact 67 and later switch blade 66 is moved into engagement with contact 68. Switch actuating arms 69 and 70 are designed to cooperate with snap switches 72 and 73. Snap switches 72 and 73 each comprise a switch blade adapted to move with a snap actuation out of engagement with one contact and into engagement with another contact or a fixed stop. The snap switch 72 comprises a switch arm 74 normally in engagement with a contact 75 and adapted to move into engagement with a contact 78. Associated with the arm is snap action mechanism (not shown) and a button 76. Upon the button 76 being pushed inwardly, the arm 74 is moved with a snap action out of engagement with contact 75 and into engagement with contact 78. The snap switch 73 comprises a switch blade 80 which is normally in engagement with contact 81 and a switch actuating button 82 which upon being pressed inwardly causes the switch blade 80 to be moved

75 with a snap action out of engagement with contact 81 and into engagement with a stop 83.

The two snap switches 72 and 73 may take any conventional form, one desirable form being that shown in the patent to Albert E. Baak No. 2,318,734 dated May 11, 1943.

The switch blades 65 and 66 and the switch actuating arms 69 and 70 are so spaced with respect to the associated contacts and the switch actuating buttons 76 and 82, that upon the element 64 being heated, snap blade 65 is first moved out of engagement with contact 67, switch actuating arm 69 is next moved into engagement with switch actuating button 76 to move switch blade 74 out of engagement with contact 75 and into engagement with contact 78, switch actuating arm 70 is next moved into engagement with switch actuating button 82 to move switch blade 80 out of engagement with contact 81, and finally switch blade 66 is moved into engagement with contact 68.

The numerals 1, 2, 3, and 4, enclosed in circles have been applied to the drawing to indicate the order in which the various switch blades and switch actuating arms are actuated.

A thermal safety switch is designated by the reference numeral 85. This comprises a pair of switch blades 86 and 87 which are biased apart but are held in engagement by a bi-metallic element 88. Associated with the bi-metallic element 88 is an electric heater 89. The bi-metallic element 88 is so arranged that upon being heated by the heater 89, it warps to the left so as to tend to move out of engagement with switch blade 87. If the heating continues until bi-metallic element 88 moves out of engagement with switch blade 87, switch blade 87 moves away from switch blade 86 and it is necessary manually to reclose the switch blades.

Operation

The various elements are shown in the position that they assume when the temperature to which the thermostat 25 is responsive is at or above the desired value so that there is no demand for burner operation. Now let it be assumed that this temperature drops so as to cause the sequential engagement of contact blades 27 and 28 with contacts 29 and 30. No energizing circuit is established until both contact blades 27 and 28 have engaged with contacts 29 and 30. When this happens, an energizing circuit is established to relay winding 42 as follows: from the right-hand terminal of secondary 33 through conductor 92, contact 29, contact blades 27 and 28, contact 30, conductors 93 and 94, contact 67, switch blade 65, conductor 95, heater 89, conductor 96, switch blades 87 and 86, conductor 97, relay winding 42, and conductor 98 to the other terminal of secondary 33. The establishment of this energizing circuit to relay coil 42 causes switch blades 43, 44, and 45 to be moved into engagement with contacts 46, 47, and 48.

The engagement of switch blade 44 with contact 47 establishes a holding circuit for relay winding 42 as follows: from the right hand terminal of relay winding 33 through conductor 92, contact 29, contact arm 27, bi-metallic element 26, conductor 98, switch blade 44, contact 47, conductor 94, contact 67, switch blade 65, conductor 95, heater 89, conductor 96, switch blades 87 and 86, conductor 97, relay winding 42 and conductor 98 to the other terminal of secondary 33. It is noted that the new circuit is independent of contact blade 28 and contact 30. Thus,

as the temperature rises, the apparatus is not placed out of operation until the temperature has risen sufficiently to cause separation of contact blade 27 from contact 29. This insures against chattering of the relay due to any rapid fluctuation in temperature or vibration of the thermostat.

The movement of switch blade 45 into engagement with contact 48 causes the following energizing circuit to be established to relay winding 50: from line wire 37 through conductor 101, contact 48, switch blade 45, conductors 102, 103, and 104, switch blade 74, contact 75, conductor 105, relay winding 50, and conductors 106, 107, 108, and 109 back to the other line wire 36. The energization of relay winding 50 causes switch blades 52 and 53 to be moved into engagement with contacts 54 and 55. The engagement of switch blade 52 with contact 54 establishes a new holding circuit to relay coil 42 as follows: from the right hand terminal of secondary 33 through conductor 92, contact 29, contact blade 27, bi-metallic element 26, conductor 99, switch blade 44, contact 47, conductor 111, switch blade 43, contact 46, conductor 112, switch blade 52, contact 54, conductors 113 and 95, heater 89, conductor 96, switch blades 87 and 86, conductor 97, relay winding 42, and conductor 98 to the other terminal of secondary 33. It will be noted that the new circuit is independent of switch blade 65 and contact 67 of timing switch 63. The original energizing circuits included this switch 65 and contact 67 so that it was necessary for timer 63 to be in its cold position before the system could be placed into operation. It is desirable, however, after this first check has been made to cause energization of the relay 40 to be independent of the time switch so that it will not be deenergized when the time switch begins to move the various switches associated with it upon being heated.

The movement of switch blade 45 into engagement with contact 48 also establishes the following energizing circuit to the primary of the ignition transformer 16: from line wire 37 through conductor 101, contact 48, switch blade 45, conductors 102 and 115, contact 81, switch blade 80, conductor 116, ignition transformer 16, and conductors 117 and 109 to the other line wire 36. The establishment of this energizing circuit results in a spark being produced across the electrodes 19 and 20 if the ignition means is functioning properly. If this spark is established, the spark begins to heat up the hot junction of thermocouple 61.

The engagement of blade 45 with contact 48 also establishes the following energizing circuit to bi-metallic element 64: from line wire 37 through conductor 101, contact 48, switch blade 45, conductors 102, 103, and 119, bi-metallic element 64, and conductors 120, 107, 108, and 109 back to the other line wire 36. The establishment of this energizing circuit to bimetallic element 64 causes the latter to begin to heat so as to move switch blades 65, 66, and switch actuating arms 69 and 70 towards the left. As previously explained, the first element to be moved is switch blade 65 which moves out of engagement with contact 67 and thus interrupts the original energizing and holding circuits to relay winding 42. Since, however, a new holding circuit has been established as described above, relay coil 42 remains energized despite the separation of switch blade 65 from contact 67. After a predetermined period of time sufficient for the thermocouple 61 to be heated by the ignition spark if the ignition

means is functioning satisfactorily, switch actuating arm 69 is effective to move switch blade 74 out of engagement with contact 75 and into engagement with contact 78. When this happens, the energizing circuit to relay coil 50 is interrupted so that relay 41 will move to its deenergized position unless relay coil 51 has become energized by reason of thermocouple 61 being heated by the actuating means. If the relay 41 does move to its deenergized position, it will interrupt the holding circuit to relay coil 42 causing it to be deenergized. The deenergization of relay coil 42 will in turn result in the bi-metallic element 64 of timer 63 and the ignition transformer 16 being deenergized. Since relay coil 42 cannot be reenergized until the timer 63 has moved back to its cold position so as to reengage switch blades 65 with contact 67, it is necessary for the system to recycle completely.

If, however, the ignition means operates properly, relay 41 will remain in its energized position holding switch blade 53 in engagement with contact 55. Under these conditions, the engagement of switch blade 74 with contact 78 will cause the following energizing circuit to be established to burner motor 11: from line wire 37 through conductor 101, contact 48, switch blade 45, conductors 102, 103, and 104, switch blade 74, contact 78, conductor 123, contact 55, switch blade 53, conductor 124, motor terminals 12 and 13, and conductors 125, 108, and 109 back to the other line winding 36. The establishment of this circuit results in the establishment of all the conditions necessary to combustion taking place. Under normal conditions, since the proper operation of the ignition means has already been checked, the atomized fuel mixture issuing from nozzle 14 will be ignited by the spark between electrodes 19 and 20.

At the end of a predetermined period of time after switch actuating arm 69 has actuated switch blade 74, switch actuating arm 70 is effective to actuate switch blade 80. Upon switch actuating arm 70 being moved to the left into engagement with button 82, as previously explained, switch blade 80 is moved with a snap action out of engagement with contact 81. When this happens, the circuit previously traced to the ignition transformer 16 is interrupted. The period of time between the actuation of switch blades 74 and 80 is normally sufficient to permit combustion to be properly established. Thus, in spite of the ignition being deenergized, the thermocouple 61 remains heated because of the presence of the burner flame. Relay 41, hence, remains in an energized position and thermal element 64 continues to heat.

After a further predetermined period of time, switch blade 66 of timer 63 is moved into engagement with contact 68, establishing the following new circuit to relay coil 42: from the right hand terminal of secondary 33 through a conductor 92, contact 29, contact blade 27, bi-metallic element 26, conductor 99, switch blade 44, conductor 47, conductor 111, switch blade 43, contact 46, conductor 112, switch blade 52, contact 54, conductors 113 and 128, switch blade 66, contact 68, conductor 129, contact blades 87 and 86, conductor 97, relay coil 42, and conductor 98 to the other terminal of secondary 33. It will be noted that the new circuit does not include the safety switch heater 89. The establishment of this circuit shorts out the safety switch heater so as to terminate its heating effect. The timing of time switch 63 is sufficient that this entire

sequence takes place before the bi-metallic element 88 has become heated sufficiently to move from out of engagement with switch blade 87. Hence, the system continues in operation until thermostat 25 is "satisfied."

Whenever the temperature of the medium to which bi-metallic element 26 is responsive has risen sufficiently to cause separation of contact blade 27 from contact 29, all of the circuits traced to relay coil 42 will be interrupted so as to terminate energization of the burner motor 11, the timer 63, and relay 41.

The system cannot be again placed into operation until the temperature has dropped sufficiently to cause reengagement of contact blades 27 and 28 with contacts 29 and 30 and until the timer 63 has been allowed to cool sufficiently to reengage switch blade 65 with contact 67 which occurs only after switch blade 66 and switch actuating armatures 69 and 70 have again assumed the position shown in the drawing. Thus, it is assured that adequate time will be provided for the thermocouple 61 to cool off before the apparatus is again placed in operation.

Operation if combustion is not initially established

It will be noted from the preceding description that when the switch blade 74 disengages from contact 75 to deenergize relay coil 50 and later when switch blade 80 disengages from contact 81 to deenergize the ignition, the relay 41 moves to its deenergized position unless the mechanism is properly operating. In the first case, the proper operation involves the proper operation of the ignition means. In the second case, it involves the establishment of combustion. In either case, the movement of relay 41 to deenergized position causes deenergization of relay 40 and timer 63 and stops all operation of the system until switch blade 65 of timer 63 reengages contact 67. If at this time, both the thermostat contact blades 27 and 28 are in engagement with contacts 29 and 30, the cycle is started over again. While the heater 89 is deenergized during the time that relay 40 is deenergized, while the timer is cooling it will be obvious that when the system recycles, heater 89 will still retain a certain amount of heat. Thus, if the system again fails to operate properly, bi-metallic element 88 will be at a higher temperature than at the beginning of the first attempt to start operation of the system. Depending upon the relative timing of timer 63 and safety switch 85, the bi-metallic element 88 may be made to disengage the safety switch blade 87 and shut down the system after two or more attempts to start. It will thus be seen if combustion is not successfully established at first, one or more further attempts will be made to establish combustion. If these attempts are likewise unsuccessful, the cumulative heating of bi-metallic element 88 by heater 89 will cause the safety switch to open to shut down the system until the safety switch is manually reclosed.

Operation in case of combustion failure

If combustion failure occurs after the system has been successfully placed in operation, the thermocouple 61 will begin to cool off. The cooling of this thermocouple will result in the deenergization of winding 51 so that the relay 41 moves to its deenergized position, as previously explained. This results in the deenergization of relay 40 and consequently the deenergization of

timer 63. It is not possible for the system to again be placed into operation until timer 63 cools down to a point where the various switch blades again resume their cold positions, as in the drawing. This timing period is sufficient for the thermocouple to cool and for any unburned gases in the furnace to pass out through the stack. If, at this time, both thermostat blades 27 and 28 are in engagement with their associated contacts 29 and 30, the operation first described will be repeated. If this attempt is unsuccessful, the cycle will be repeated. In other words, a series of attempts will be made to restart the system and if these attempts are unsuccessful, the safety switch will be opened so as to shut down the system awaiting manual intervention.

Conclusion

It will be seen that I have provided a burner control mechanism employing a single element to detect both the proper operation of an actuating means and also the establishment of combustion. It will further be seen that this burner control mechanism provides for safe operation in the event of any possible type of abnormal operation.

While I have shown a specific embodiment of my invention, it is to be understood that this is for purposes of illustration and that my invention is limited only in scope by the appended claims.

I claim as my invention:

1. In control apparatus for a fuel burner control motor and ignition means; a safety controller for interrupting operation of said apparatus at the end of a timed period; a timer, means including said timer for establishing circuit connections adapted to lead to said motor means, then interrupting circuit connections adapted to control energization of said ignition means, and finally rendering said safety controller inoperative, means adapted to respond to a condition indicative both of the proper operation of the ignition means and of the presence of combustion, and means including said last named means adapted to continue operation of said timer after the circuit connections for said ignition means have been interrupted only if said condition responsive means indicates the maintenance of said condition due to the establishment of combustion.

2. In control apparatus for a fuel burner control motor and ignition means, a safety controller for interrupting operation of said apparatus at the end of a timed period, a timer, means including said timer for establishing circuit connections adapted to lead to said motor means, then interrupting circuit connections adapted to control energization of said ignition means, and finally rendering said safety controller inoperative, a temperature responsive element adapted to be located so as to be subjected to the heat produced both by the ignition means and by combustion, and means including said temperature responsive element adapted to continue operation of said timer after the circuit connections for said ignition means have been interrupted only if said temperature responsive element continues to be heated as the result of the establishment of combustion.

3. In control apparatus for a fuel burner control motor and ignition means, a safety controller for interrupting operation of said apparatus at the end of a timed period, a timer, means including said timer for first establishing circuit con-

nections adapted to lead to said ignition means, then after a first timed period establishing circuit connections adapted to lead to said motor means, then interrupting said circuit connections for said ignition means after a further timed period, and finally rendering said safety controller inoperative, means adapted to respond to a condition indicative both of the proper operation of the ignition means and of the presence of combustion, and means including said last named means and said timer adapted first to continue operation of said timer only if the ignition means is functioning properly and later after the ignition means has been deenergized to continue operation of said timer only if combustion has been established.

4. In control apparatus for a fuel burner control motor and ignition means; a safety controller for interrupting operation of said apparatus at the end of a timed period, a timer, means including said timer for first establishing circuit connections adapted to lead to said ignition means, then after a first timed period establishing circuit connections adapted to lead to said motor means, then interrupting said circuit connections for said ignition means after a further timed period and finally rendering said safety controller inoperative, a temperature responsive element adapted to be located so as to be subjected to the heat produced both by the ignition means and by combustion, and means including said temperature responsive element adapted to interrupt operation of said timer before said circuit connections for said motor are established if said temperature responsive element is not heated by said ignition means and later to interrupt operation of said timer after said ignition circuit connections have been interrupted if combustion has not been established.

5. In a fuel burner control system, a burner, ignition means therefor, a thermocouple having its hot junction located so as to be heated either by the heat produced by the ignition means or by that produced by the flame of the burner, a winding energized by said thermocouple when the hot junction of the latter is heated sufficiently; a main controller; a timer; and means including said winding, said main controller, and said timer operative upon said main controller assuming a condition calling for burner operation first to initiate operation of said ignition means, then to terminate operation of said ignition means and said timer after a first timed period if said winding has not been energized by reason of said thermocouple being heated by said ignition means, and finally to terminate operation of said ignition means after the end of a second timed period independently of said winding to cause termination of the operation of said burner and said timer if said winding does not remain energized because of the thermocouple being heated by the flame of the burner.

6. In control apparatus for a fuel burner motor and ignition means; a temperature responsive element adjacent said ignition means and exposed to the heat thereof; a time switch including an electrically energized timer and first and second switches; a relay comprising a third switch closed when said relay is energized; a main control switch; a first circuit means adapted upon closure of said main switch to cause energization of said timer, said relay and the ignition means; second circuit means including said temperature responsive element for causing said relay to re-

main in energized position independently of said first circuit means upon said temperature responsive element being heated by said ignition means; further circuit means adapted to cause energization of said burner motor upon closure of both said second and third switches; said timer being operative a period of time after closure of said main switch to open said first switch and terminate energization of said relay by said first circuit means and to close said second switch to cause energization of said burner motor by said further circuit means if said relay remains in energized position following the opening of said first switch.

7. In control apparatus for a fuel burner motor and ignition means; a thermocouple having its hot junction adjacent said ignition means and exposed to the heat thereof; a time switch including an electrically energized timer and first and second switches; a relay comprising a plurality of windings and a third switch, said third switch being closed when either one of said windings is energized; a main control switch; a first circuit means adapted upon closure of said main switch to cause energization of said timer, a first of said relay windings, and the ignition means; connections between the other of said relay windings and said thermocouple for causing said relay to remain in energized position independently of said first circuit means upon the hot junction of said thermocouple being heated by said ignition means; further circuit means adapted to cause energization of said burner motor upon closure of both said second and third switches; said timer being operative a period of time after closure of said main switch to open said first switch and terminate energization of said one relay winding by said first circuit means and to close said second switch to cause energization of said burner motor by said further circuit means if said relay remains in energized position following the opening of said first switch.

8. In a fuel burner control system; a burner; ignition means therefor; a temperature responsive element located so as to be responsive either to the heat produced by the ignition means or to that produced by the flame of the burner; a main controller; a timer; and means including said temperature responsive element, said main controller, and said timer operative upon said main controller assuming a condition calling for burner operation first to initiate operation of said ignition means, then to terminate operation of said ignition means and said timer after a first timed period if said temperature responsive element has not been heated by said ignition means, and finally to terminate operation of said ignition means at the end of a second timed period independently of said temperature responsive element to cause termination of the operation of said burner and said timer if said temperature responsive element is not maintained hot by the flame of the burner.

9. In control apparatus for a burner fuel control motor and ignition means; a time switch including an electrically energized timer and switch means operated thereby, said timer moving in one direction when energized and in an opposite direction when deenergized; a first relay adapted to control the energization of said timer, said fuel control motor, and said ignition means; circuit connections controlled by said time switch and including said first relay and adapted to include a main controlling switch and a source of power to complete an energizing circuit for said first

relay only when said timer is in its deenergized position; a second relay for also controlling said fuel control motor; means including apparatus adapted to respond both to the proper operation of said ignition means and to the establishment of combustion for causing the continued energization of said second relay only if either said ignition means is functioning properly or com-

5 bustion is established; and means controlled by said time switch and operative to cause deenergization of said ignition means a predetermined period of time after energization of said timer so that said second relay becomes deenergized if combustion has not then been established.

ISSERSTEDT.
